AUTOMATIC FILLING APPARATUS FOR LIQUID CONTAINERS

Herman Lindars, Sheffield, England

Application January 21, 1952, Serial No. 267,390

Claims priority, application Great Britain
February 20, 1951

3 Claims. (Cl. 226—127)

This invention relates to apparatus for supplying liquid to containers and it has for an object to provide apparatus whereby liquid can be supplied to a container to a predetermined limit of its capacity.

The present invention aims at ensuring that any container is filled to within a predetermined limit of its actual capacity irrespective of its nominal size and at the same time prevents spillage of the liquid.

According to the present invention apparatus for supplying liquid to a container to a predetermined level therein comprises conduit for carrying liquid to the container from which container air can escape during filling, a tube to be inserted into said container to a depth therein dependent upon the predetermined liquid level, said tube to supply low pressure air to the container, pressure responsive means connected with said tube and regulating means operated by said pressure responsive means for interrupting the flow of liquid through said conduit when the predetermined liquid level in the container is reached.

Preferably, the conduit includes a filling nozzle rigidly secured to said air supply tube to form a single unit there-with and the means for interrupting the flow of liquid through said conduit comprises an electro-magnetically operated valve.

Advantageously, the pressure responsive means is a bellows which is arranged to operate a relay connected in circuit with the electro-magnetic means of the valve, which, in a preferred form, is spring biassed towards its closed position and is normally kept open against the action of the spring by means of a lever adapted to be released by operation of the electro-magnet.

A preferred embodiment of the invention which is illustrative only thereof, will now be described with reference to the accompanying drawing.

The apparatus comprises a nozzle 1 for filling a container 2 with liquid which is connected to the liquid supply line 3 through a shut-off valve 4 which is spring-loaded to the closed position. The valve 4 is held open by means of a lever 5 which is pivoted at 6 adjacent the free end of the valve stem 7 and is retained in the valve opening position by means of a latch 8 which engages the free end of the lever 5. The latch carries an armature 9 for an electro-magnet 10 which is energised from supply mains 11 through a pair of electro-magnetic relay contacts 12a and 12b which close when the relay 13 is energised. The circuit to the relay 13 comprises a pair of contacts 14a and 14b mounted adjacent a tail piece 15 on the shut-off valve lever 5 and adapted to be closed when the lever 5 is latched to hold the valve 4 open. These contacts 14a and 14b are connected in series with a second pair of normally closed contacts 16a and 16b which are arranged to be opened by a bellows or like pressure responsive relay 17. The relay 13 controlling the circuit to the electro-magnet 10 is thus normally energised so that the latch 8 is positively held in engagement with the lever 5. A spring 18 biases the latch 8 to the release position so that when the electro-magnet 10 becomes de-energised

2

the shut-off valve 4 closes under the action of its loading spring 19.

The bellows 17 is open to atmosphere on one side 17a and on the other side 17b is connected to a relatively narrow bore air tube 20 which terminates at its lower end 21 close to, and slightly above, the mouth of the liquid nozzle 1. The lower portion of this air tube 20 is secured to or formed integrally with the liquid nozzle 1, whilst the upper end above the connection to the bellows 17 is provided with a needle valve 22 for controlling the flow of air through the tube 20. Beyond the needle valve 22, connection is made to a low pressure air-supply (not shown).

Surrounding the nozzle 1 and the lower end of the air tube 20 is a collar 23 which is adjustably clamped to the nozzle 1 to define the extent to which the air tube 20 projects into the container 2. The collar 23 is adapted to rest on the rim 24 of the filling aperture 25 in the container 1 in such a manner that it does not constitute an airtight seal. If desired, the lower surface of the collar 23 may be provided with flutes or corrugations (not shown) to ensure that no seal can be formed.

In operation, the collar 23 is adjusted on the liquid nozzle 1 so that the air tube 20 projects into the container 2 slightly below the level L to which it is to be filled. The amount by which the open end 21 of the tube 20 lies below this level will depend on the calibration of the bellows 17. The liquid nozzle 1 with the attached air pipe 20 is then inserted into the container 2 and the needle valve 22 in the air tube 20 is opened to allow air to leak down the tube 20 and escape through the filling orifice 25 of the container 2. Since the air is thus free to escape, there is no differential pressure developed across the bellows 17 and the contacts 16a and 16b operated thereby remain closed.

When filling is to be commenced, the shut-off valve 4 is opened by engaging the lever 5 with the latch 8, thereby causing the contacts 14a and 14b operated by the tail-piece 15 on the lever 5 to close. The electro-magnetic relay 13 is thereupon energised to close its contacts 12a and 12b and so in turn to energise the electro-magnet 10 which holds the latch 8 in engagement with the shut-off valve lever 5. Liquid thereupon flows into the container 2 and the level rises therein.

When the liquid level reaches the bottom of the air tube 20 an air seal is formed and pressure begins to build up in the air tube 20 between the needle valve 22 and the lower end of the tube 20. This pressure appears across the bellows 17 and in a short time builds up to a sufficient value to operate the bellows 17 and so open the normally closed contacts 16a and 16b controlled thereby. These contacts break the circuit to the electro-magnetic relay 13 which thereupon releases its contacts 12a and 12b to open the circuit of the electro-magnet 10. The latch 8 is then returned to its free position by the spring 18 and releases the shut-off valve lever 5. The supply of liquid is thereupon cut off by closure of the valve 4 under the action of its spring 19.

It will be seen that the apparatus functions to ensure the automatic cut-off of the supply of liquid to a container 2 when the level of the liquid therein rises above the level of the open end of the air tube 20 by an amount sufficient to constitute a seal against the relatively low air pressure in the air tube 20. The amount by which the level must rise to effect a cut-off of the liquid supply is thus partly dependent on the air pressure below the needle valve 22 and the sensitivity of the bellows 17 or other pressure responsive relay means.

Various modifications of the above arrangement can be made as will be understood. Thus, for example, the air tube can be separated from the liquid nozzle and placed at a different part of the containers where errors due to

splashing or turbulence in the vicinity of the nozzle are reduced to a minimum. Where the apparatus is to be used for filling containers with chemicals under controlled atmosphere conditions, any inert gas may be used in place of air in the air tube. In this specification, the term "air" is to be understood as including any form of gas.

The circuit for controlling the shut-off valve in the liquid supply line may be modified in any suitable manner and may be partially or wholly of a pneumatic or hydraulic nature if preferred. The bellows may also be replaced by a diaphragm or even a piston and cylinder type of motor, if desired.

The invention is applicable to the filling of all liquid containers including those which are permanently connected to a liquid supply line for intermittent filling, in which case the air tube may also be a permanent fitting. Should it be necessary to vary the level of liquid discharged into such containers, provision may be made for the adjustment of the height of the open end of the air tube in the manner described above.

What I claim:

1. Apparatus for supplying liquid to a receptacle up to a predetermined level therein comprising a liquid discharge nozzle, a valve for controlling the liquid flow through the nozzle, a valve operating lever resiliently biased to the closed position, a detent engageable with the operating lever to hold it in the open position, an electromagnet for holding the detent in its engaged position, an air pressure pipe connected to said nozzle and terminating at a point corresponding to the said predetermined level, a single pneumatic relay communicating with the said pipe, and contacts controlled by said relay for de-energising the electromagnet on operation of the relay by a rise in air pressure in the pipe.

2. Apparatus for supplying liquid to a receptacle up to a predetermined level therein comprising a liquid discharge nozzle, a valve for controlling the liquid flow

5

through the nozzle, a valve operating lever resiliently biased to the closed position, a detent engageable with the operating lever to hold it in the open position, an electromagnet for holding the detent in its engaged position, an air pressure pipe connected to said nozzle and terminating at a point corresponding to the said predetermined level, a single pneumatic relay communicating with the said pipe, a first pair of contacts adapted to be opened by the pneumatic relay on a rise in pressure in the pipe, a second pair of contacts in series with the said first pair and adapted to be closed by the valve operating lever when engaged by the detent, and an electromagnetic relay in the circuit of said contacts for controlling the energisation of the detent electromagnet when the valve operating lever is moved to the open position.

10

3. Apparatus for supplying liquid to a receptacle to a predetermined level, comprising a liquid discharge nozzle, a valve for controlling the liquid flow through the nozzle, a valve operating lever resiliently biased to the closed position, a detent engageable with the operating lever to hold it in the open position, an electromagnet for holding the detent in its engaged position, an air pressure pipe connected to said nozzle and terminating at a point corresponding to said predetermined level, a single pneumatic relay communicating with said pipe, and means controlled by the pneumatic relay and responsive to a rise in pressure in the air pressure pipe for deenergizing said electromagnet to close said liquid control valve.

15

20

4. Apparatus for supplying liquid to a receptacle to a predetermined level, comprising a liquid discharge nozzle, a valve for controlling the liquid flow through the nozzle, a valve operating lever resiliently biased to the closed position, a detent engageable with the operating lever to hold it in the open position, an electromagnet for holding the detent in its engaged position, an air pressure pipe connected to said nozzle and terminating at a point corresponding to said predetermined level, a single pneumatic relay communicating with said pipe, and means controlled by the pneumatic relay and responsive to a rise in pressure in the air pressure pipe for deenergizing said electromagnet to close said liquid control valve.
